UNITED STATES PATENT OFFICE.

MARY C. ARMSTRONG, OF PERTH AMBOY, NEW JERSEY.

FLY-CATCHER.

1,083,179.

Specification of Letters Patent. Patented Dec. 30, 1913.

Application filed October 3, 1911. Serial No. 652,494.

To all whom it may concern:

Be it known that I, MARY C. ARMSTRONG, a citizen of the United States, and a resident of Perth Amboy, in the county of Middlesex and State of New Jersey, have invented a new and Improved Fly-Catcher, of which the following is a full, clear, and exact description.

Among the principal objects which the present invention has in view are: to provide means for holding adhesive paper or material in a manner to protect the same from accidental contacting with adjacent articles; and to provide a frame for supporting adhesive material or paper for disposing the same in convenient position and for otherwise handling the trap.

One embodiment of the present invention is disclosed in the structure illustrated in the accompanying drawings, in which like characters of reference denote corresponding parts in all the views, and in which—

Figure 1 is a side view of a trap constructed and arranged in accordance with the present invention; Fig. 2 is a similar view taken from the opposite side of the trap; and Fig. 3 is a longitudinal section taken on the line 3—3 in Fig. 1.

The embodiment of the invention portrayed in the accompanying drawings consists in providing a heavy wire frame 8, bent to any desired shape, the preferred form being shown in the drawings, and best seen in Fig. 2 thereof. The wire composing the frame 8 is twisted upon itself to produce the handle 9, at the end whereof is formed an eyelet 10. Suitably secured to the frame 8 is a wire gauze filling 11. The filling may be constructed from woven wire, the mesh whereof is of any desired size. By means of the eyelets 12 a second frame 13 is hinged to the first mentioned frame 8. The frame 13 is substantially the same in shape as the frame 8, and may be given a permanent shape or form by the loose sides which are each provided with hook-like ends 14, 14. It is preferred to form the sides of the frame 13 independently, that the said sides may be spread outward to adapt themselves more readily to the adjustment of the paper 15 carrying the adhesive or entangling surface common to so-called fly paper. The paper 15 is preferably formed to the shape shown

in the drawings corresponding to the frame 8. However, the paper may be provided in any suitable form and trimmed after it is secured between the frames 8 and 13.

With a device thus constructed the operation is as follows: The ends of the frame 13 are released and the frame thrown back to the position as indicated by the broken lines in Fig. 1. The paper 15 is then disposed on the frame 8, the adhesive surface resting lightly upon the wire of the filling 11. The frame 13 is then drawn over the edges of the paper 15 and the ends 14 of the sides of the frame 13 are wrapped about the handle 9, as seen best in Fig. 2 of the drawings. The tension of the resilient material from which the frame 13 is constructed holds the ends 14, 14 locked upon the handle 9. When thus equipped the trap may be moved from point to point, or waved gently through the air by the attendant grasping for that purpose the handle 9. If the frames 8 and 13 be formed on so-called rotary fans or fly fans, the construction will be substantially the same as herein described for the hand operated trap. By means of the eyelet 10 the trap may be moved from point to point, or may be hung upon the wall or other convenient position.

In the preferred form the filling 11 and frames 8 and 13 are constructed from bright tinned wire, which may be sterilized at any time by being dipped in suitably heated water.

Having thus described my invention, what I claim as new and desire to secure by Letters Patent is:—

A holder for fly paper comprising an open mesh screen having a marginal frame, a back adapted to hold the paper against the screen; the back consisting of a frame hinged to the screen frame and adapted to engage the edges of the paper, a handle on the screen frame by means of which the device may be waved through the air, and means for locking the back in closed position.

In testimony whereof I have signed my name to this specification in the presence of two subscribing witnesses.

MARY C. ARMSTRONG.
